UNITED STATES PATENT OFFICE.

JIRO MIYABARA, OF TOKIO, JAPAN.

WATER-TUBE BOILER.

SPECIFICATION forming part of Letters Patent No. 747,080, dated December 15, 1903.

Application filed October 12, 1903. Serial No. 176,626. (No model.)

To all whom it may concern:

Be it known that I, JIRO MIYABARA, a subject of the Emperor of Japan, and a resident of Tokio, Japan, have invented a new and useful Improvement in Water-Tube Boilers, of which the following is a specification.

This invention is an improvement on the water-tube boiler described in my Letters Patent of the United States No. 633,699, dated

September 26, 1899; and its object is to provide a simple and efficient water-tube boiler in which there shall be an effective circulation of water and steam.

It has more particularly for its object to provide a structure in which the steam which is produced is passed from the top chamber or chambers of the boiler through a series of tubes into a steam drum or chamber, so as to become superheated to a material degree by the gases of the combustion-chamber.

In the accompanying drawings, Figure 1 is a vertical section of one form of a boiler containing my present invention. Fig. 2 is a vertical section of another form thereof. Fig. 3 is a vertical section of a third form thereof. Figs. 4 to 10, inclusive, are details.

1, 2, 3, 4, 5, and 6 are horizontal water-drums arranged in two vertical series to form the front and back walls of the combustion-chamber 7. The drums in each vertical series are connected together by the interposed junction-boxes or vertical tubes 8. The two combustion-chamber water-walls thus constructed are connected together by the series 35 of water-tubes 9, which extend diagonally across the combustion-chamber above the fire-grate 10. In each of the water-drums, excepting the top and bottom ones, is preferably provided a diaphragm or deflector 11, so arranged as to separate the streams of water and steam circulating upwardly through the water-tubes 9 from the stream of water circulating downwardly through the junction-boxes 8. The water-level in the boiler 45 is at 12, so that the uppermost of the drums already referred to constitute combined water and steam drums.

13 is a steam drum or chamber located above the water-level in the position shown 50 in either of the drawings.

14 and 15 in Figs. 1, 2, 4, 5, and 7 are two series of steam-tubes which connect the

steam-drum 13 with the combined steam and water drums 1 and 2, respectively. In Figs. 3 and 6 there is only one series of tubes 14, 55 which connects the steam-drum 13 with the combined steam and water drum 1 or 2. When arranged as shown in Fig. 6, the tops of drums 1 and 2 should be connected by a pipe 16 for conveying steam from one to the other.

22, 23, 24, and 25 are deflecting-plates within the combustion-chamber compelling the gases to pursue a circuitous course among the water-tubes. 65

26 is the flue.

For detaining the steam after leaving the steam and water drums of the boiler within the superheating-gases of the combustion-chamber I provide a circuitous passage from 70 the steam and water drums to the steam-drum 13. The mechanical construction by which such passage is made circuitous may be greatly varied; but the following are examples: As shown in Figs. 4 and 5, it consists of the casings 17, 18, 19, and 20, inclosing the ends of the tubes 14 and 15, so as to compel the steam to take the circuitous route indicated by the arrows, and thus pass repeatedly through each series of pipes. These 80 casings may be made of cast or wrought iron or steel or other suitable metal and so constructed that they may be removed in order to clean, examine, or replace the superheating-tubes. As shown in Figs. 9 and 10, said 85 mechanical construction consists of a spiral deflector-plate 21, inserted in each of the tubes of the series 14 and 15, whereby the steam is given a circuitous course as it passes through each of said tubes. As shown in Fig. 7, said 90 mechanical construction consists in giving each of the pipes in the series 14 and 15 a loop form, so that each pipe substantially crosses the combustion-chamber and returns to the drum 13. I do not wish to limit my- 95 self to either of said forms of construction.

Having thus described my invention, I claim as new and desire to secure by Letters Patent—

1. In a water-tube boiler, in combination 100 two series of horizontal water-drums constituting opposite walls of the combustion-chamber and extending above the water-level, oppositely-inclined water-tubes connecting

said two series across the combustion-chamber, a steam-drum and a series of steam-pipes in the combustion-chamber connecting one or more of said water-drums above the water-level with said steam-drum.

2. In a water-tube boiler, in combination, two series of connected horizontal water-drums constituting opposite walls of the combustion-chamber, a superheated steam-receiver drum, pipes connecting said steam-receiver drum with said water-drums provided with means whereby the steam is given a circuitous course after leaving said water-drums.

3. In a water-tube boiler, in combination, front and back water-drums, a superheated steam-receiver drum, a series of steam-pipes connecting said water-drums with said steam-drum, casings located within said drums whereby the steam is compelled to pass repeatedly through said series of pipes and spiral guide-strips inserted in said steam-pipes.

4. In a water-tube boiler, in combination, two series of connected horizontal water-drums constituting opposite walls of the combustion-chamber and extending above the water-level, oppositely-inclined water-tubes

connecting said two series across the combustion-chamber, a steam-drum exposed to the upper portion of said combustion-chamber above the water-level and a series of pipes also exposed to the upper portion of said combustion-chamber and connecting said water-drums above the water-level with said steam-drum.

5. In a water-tube boiler, in combination, two series of connected horizontal water-drums constituting opposite walls of the combustion-chamber and extending above the water-level, oppositely-inclined water-tubes connecting said two series across the combustion-chamber, a steam-drum located above the space between said two series of water-drums, two series of steam-pipes exposed to the products of combustion and connecting both of said series of water-drums with said steam-drum above the water-level.

In testimony whereof I have hereunto signed my name in the presence of two subscribing witnesses.

JIRO MIYABARA.
